TRICK WALKING CANE

Bernard V. Lukowitz, Milwaukee, Wis.

Application July 12, 1946, Serial No. 683,237

2 Claims. (Cl. 135—47)

1

My invention refers to a trick cane, such as disclosed in my Patent Number 2,385,091, dated September 18, 1945.

The particular object of my invention is to provide a simple fountain cane, carrying a squeeze bulb in its handle, in check valve communication with the hollow fountain body of the cane stem and ferrule, whereby upon a hand squeeze of the bulb, it will discharge a fine stream of fluid, through the ferrule, it being understood that the fluid loaded cane, will repeat the discharge impulses indefinitely, depending upon the volume of liquid stored in said cane.

With the above and other objects in view, which will appear as the description proceeds, the invention resides in the novel construction, combination and arrangement of parts, substantially as hereinafter described, and more particularly defined by the appended claims, it being understood that such changes in the precise embodiment of the herein disclosed invention may be made as come within the scope of the claims.

In the accompanying drawings is illustrated one complete example of the physical embodiment of the present invention constructed according to the best mode so far devised for the practical application of the principles thereof.

In the drawings:

Figure 1 represents an elevation of a fountain cane embodying the features of my invention, parts being broken away and partly in section to more clearly illustrate structural features.

Fig. 2 is a cross section of the same through the ferrule, the section being indicated by line 2—2 of Figure 1.

Fig. 3 is a fragmentary view of the ferrule and fluid connections modified in form.

Referring by characters to the drawings, 1 indicates a hollow cane stem, having fitted to its upper end an offset handle 2.

The under-face of the handle has secured thereto, a flexible squeeze bulb 3 having a hollow neck 4 in communication therewith, the same being extended through a channel 5 in the handle shank.

Below the shank of the neck 4, it terminates with branch sections 4' and 4''.

The branch section 4' is connected to a flexible tube 6, the lower end of which tube is fitted to the extended end of a cored plug 7 seated into the bottom end of the cane stem. The lower end of the plug is shouldered, and secured to the mouth 7', is a chambered tip 8, the plug and tip together forming a ferrule.

The chambered tip 8 is provided with a diagonal

2

upwardly inclined bleed 8', for the discharge of a fine stream of liquid.

Nested between the base of the plug 7 and a shouldered portion of the chamber 8, and the chamber tip 8', is a flexible diaphragm disc 9, which disc, as best indicated in Figure 2 of the drawings, is provided with a central fluid discharge slit 9'.

The disc, so positioned, serves as a discharge check valve, whereby fluid from the cored plug is delivered to the chamber portion of the tip 8.

The fluid re-fill, of the hollow cane stem, is obtained through an aperture 10 in said stem, at its upper end, the same being closed by any suitable stopper 10'.

The branch section 4'' of the neck 4 communicates with a suction tube section 11, which tube section terminates in juxtaposition to the ferrule, or near the bottom of the stem fluid contents.

20 The suction tube has fitted into its bottom end a nipple 12, which nipple carries an intake check valve ball 12'.

From the foregoing description, it is obvious, when the squeeze bulb 3 with its ferrule connections, is squeezed, a thin spray of fluid is discharged from the ferrule, with each squeeze movement of the bulb.

When the bulb 3 is freed from hand pressure, it will expand to its normal area and in so doing 30 will create a suction through the neck 4 and check valve controlled nipple 12, whereby the fluid is sucked from the bottom of the hollow stem. Thus a pumping action, in effect, is developed.

It is understood, in some instances, a single 35 discharge tube 6 may be employed, in connection with a valve controlled intake nipple 12, which communicates, by a branch tube 13, with the tube 6 adjacent to the ferrule, whereby the length of the tube 11 is dispensed with.

40 I claim:

1. In a hollow stemmed cane having an offset handle; the combination of a ferrule for the stem comprising a chambered tip having a discharge orifice, a cored plug nested into the tip, a discharge check valve fitted between the plug and tip, an exposed squeeze bulb nested in the cane handle, a tube connecting the bulb and cored ferruled plug, an intake nipple communicating with the tube adjacent to the ferrule and an intake 50 check valve mounted in the nipple.

2. In a hollow stemmed cane having an offset handle; a ferrule therefor, comprising a chambered tip having an orifice in communication therewith, a cored plug communicating with the orifice tip, a discharge check valve carried there-

by, a squeeze bulb fitted to the cane handle, a tube communicating with the bulb and ferrule, a second tube section in communication with the first mentioned tube and an intake suction valve nipple carried at the end of said last mentioned tube section.
